UNITED STATES PATENT OFFICE

2,096,986

BRAUN TUBE

Manfred von Ardenne, Berlin, Germany, assignor
to Radioaktiengesellschaft D. S. Loewe, Berlin-
Steglitz, Germany, a company of Germany

Original application May 16, 1932, Serial No.
611,568. Divided and this application April 17,
1933, Serial No. 666,554. In Germany March
27, 1931

7 Claims. (Cl. 250—27.5)

The invention relates to improvements for fluorescent screens preferably for screens in Braun tubes for television devices.

It will be appreciated that as regards the construction of scanning transmitters employing Braun tubes it is of fundamental importance that all elements reveal a minimum sluggishness in operation. In the case of the television transmission means heretofore employed having cathode ray tubes use has been made of the phosphorescent effect, which in itself supplies considerable amounts of light energy. It is well known that by phosphorescent effect in the case of screens erroneously termed fluorescent screens there is meant a luminosity, which does not instantaneously follow on the excitation of the cathode ray, and also requires a certain time to die down. In the case of certain silicates, such for example as zinc silicate, these cessation periods, so-called fading periods, are in the order of one-tenth of a second, and in some cases are even higher in order.

As already mentioned above, it is necessary for the purpose of reproduction without distortion to employ at the transmission end only those elements which are void of sluggishness. The materials above referred to do, therefore, not enter into the question as screen material for television transmitters. As experiments have shown, properties of a much more favourable kind as regard the object concerned are disclosed by calcium and cadmium tungstate. The lighting-in and fading periods of these materials are in the order of 10-5 seconds. Even the sluggishness of these materials, however, is too great for television rich in detail. An ideal material for the screen of a cathode-ray television transmitter would be a screen material which utilizes solely the fluorescent effect, whereby there is understood by fluorescent in its usual meaning a luminous effect, which commences instantaneously with the excitation and terminates instantaneously with cessation of the excitation.

According to the existing state of scientific knowledge it is assumed that a cathode-ray fluorescence does not exist at all. Now with the assistance of special measuring means, which cover the quantitative comprehension of high-frequency fluctuations in light, the applicant has been successful in establishing that, in contradistinction to the previous assumption, a cathode-ray fluorescence does in point of fact exist. Certainly, the fluorescence supplies approximately one to two tenth powers less light than the phosphorescence. This is apparently also the reason

why the same has not been observed heretofore. The light phosphorescence covers the weak fluorescence, as will be more clearly described below. In order to make the invention fully understood, reference will be had to the accompanying drawing,

Fig. 1 of which shows the cathode ray excitation of an element of the luminous screen as dependent on time, whereas

Fig. 2 shows the corresponding fluorescence and phosphorescence phenomena.

In Fig. 3 the amplification degree of a photocell amplifier preferably employed according to the invention is shown as dependent on frequency.

Fig. 4 illustrates a complete television system according to the invention.

In Fig. 1 the shock excitation of the cathode ray of a screen-surface element is shown dependent on time. It is assumed, for example, that this exciting impulse amounts to one-millionth of a second. There then occurs instantaneous excitation of the screen-surface element to the extent of fluorescence and a phosphorescent effect which commences slowly, but proceeds much more pronouncedly and dies down very gradually. This is more clearly shown in Fig. 2, in which there is illustrated the amount of light dependent on time, on the one hand in respect of the fluorescent effect and on the other hand in respect of the phosphorescent effect.

According to the invention, it is the intention, for the purpose of image reproduction free of distortion, to employ the screen fluorescence alone, or at least for the greater part, in the television transmitter for the very rapidly occurring variations in the excitation of the screen. In frequency ranges below 100,000 periods the strong phosphorescent effect is not of a detrimental kind, as it is possible with the assistance of present-day distortion-correcting methods in the amplifier to provide this with a frequency characteristic of such nature that the strong phosphorescent effect in the case of low frequencies results in the same output potentials as the weak fluorescent effect in the case of higher frequencies. The separation of phosphorescent and fluorescent effects in the case of relatively low frequencies is more difficult, and is also not essential, whereas in the case of high frequencies this results automatically, the phosphorescent effect being of such a sluggish nature that the same supplies a constant intensity amplitude as compared with the rapidly occurring variations in the excitation.

Accordingly, there is preferably employed for

5

45

50

55

the photo-cell potential an amplifier such as illustrated in Fig. 3. In the latter the degree of amplification V is shown as being dependent on f (in periods).

- 5 In order to cause the weaker fluorescent effect to also produce in the photo-cell amplifier of the transmitter potentials which are situated above the shot mark (Schrotpegel), very appreciable beam energies may possibly require to be 10 converted in the cathode ray tube of the transmitter, for example beam currents of $\frac{1}{8}$ -1 milliampere at 3-10 kv speed.

To avoid necessity for excessive differences in the frequency characteristic of the transmission 15 amplifier, materials are preferably employed in which the phosphorescent effect remains as small as possible in comparison with the fluorescent effect. Under certain circumstances the use of a special distortion-correcting means within the 20 amplifier may not be necessary at all. The materials concerned in this connection have heretofore been ignored as material for the screen on account of their low absolute degree of light. The same acquire importance only by reason of 25 the recognitions set forth in this application. A material, for example, disclosing practically no phosphorescence is plaster, which accordingly is admirably suited as a screen material for Braun tubes employed as television transmitters.

- 30 As already mentioned, the electro-optical efficiency requires to be considerably larger than has been the case in connection with the tubes hitherto known for carrying out a television method of a useful kind with Braun tubes.
- 35 In the case of the fluorescent screens employed heretofore in connection with Braun tubes various disadvantages have been found to exist, which it is intended to avoid by the present invention. In the first place the screens hitherto 40 in use, which in their finest quality consist of calcium tungstate, suffer from a sensitiveness which for numerous purposes is too small, i. e., from an insufficient electro-optical efficiency. This lack of sensitiveness has been found extremely disturbing, particularly in the case of 45 Braun tubes intended to be employed for television purposes.

According to the invention, cadmium tungstate is employed for the coating. This cadmium tungstate may, in the manner heretofore known in association with other substances, be mixed with waterglass and painted on to the glass wall in question.

- 50 A similar or additional improvement in the electro-optical efficiency may be accomplished by not mixing the fluorescent material with the attachment substance, but at first evenly distributing the attachment substance, preferably waterglass, over the surface to be furnished with 55 fluorescent material, for instance painting the same into the tube, and then allowing it to somewhat run until the layer has assumed an even character, the fluorescent material, preferably cadmium tungstate, then being applied in finely 60 divided condition, preferably by means of a nozzle. It is thus accomplished on the one hand that the crystalline structure of the fluorescent material is maintained, and on the other hand that the rays inciting fluorescence meet in direct 65 fashion against the sensitive material, and finally that the layer is substantially more even and homogeneous. As a result of these properties the sensitiveness of the layer is raised to a maximum, so that the sensitiveness is equal at all 70 points, which is an absolute necessity for fault- 75

less television images, and finally there is extremely little waste in manufacture. A method of this kind for producing the fluorescent screen is naturally of advantage not only in the case of a screen material consisting of cadmium tungstate, but also in connection with all other materials, inasmuch as the screen materials employed behave, generally speaking, in practically equivalent manner from a working-technical standpoint, and the sodium waterglass hitherto 10 generally in use for binding purposes results in all cases in appreciable deterioration of the luminosity. Sodium waterglass has, however, the disadvantage that the same causes a darkening effect on the luminous surface. According to 15 the invention, this is avoided by the fact that in place of sodium waterglass there is employed as binding agent potassium waterglass. This is naturally not only suitable as a binding agent for cadmium tungstate, but also for the majority of 20 fluorescent materials hitherto in use, such for example as zinc silicate phosphor.

By reason of the high insulating power of glass charges giving rise to disturbances frequently accumulate on the screen in the case of tubes 25 of this kind. These charges cause variation in the speed of the ray, and accordingly intensity distortion; at the same time, however, they also cause spot displacement, even if only a slight one, dependent on the extent of the discharge 30 and its distribution on the surface. To be able to conduct away these charges with sufficient rapidity, it is necessary, assuming the screen does not permit of leaking off per se, to provide a special leak conductance layer which, for example, at the same time also constitutes the binding 35 agent for the fluorescent substance. It is, however, also possible, for instance, to produce an extremely thin layer by cathode atomization or by spraying on graphite or carbon, which ensures 40 a sufficient leak conductance for the charges. This conductive layer, or the screen respectively, assuming the same is sufficient, is preferably connected with the anode of the Braun tube.

Generally speaking, it is not to be avoided that 45 certain, in particular slow rays disperse from the bundle, which is concentrated in itself, and thus lead to troublesome conjoint lighting effects on the part of other surface portions of the fluorescent coating. To avoid this there is, according 50 to the invention, applied to the coating produced in accordance with the above process a thin, preferably transparent protective layer, which renders the dispersed rays, which as regards their intensity are considerably below that of the main beam, without effect. This preferably transparent protective layer, which may consist, for example, of potassium waterglass, may be employed particularly in the present case, since in accordance with the above method it is possible in itself to raise the sensitiveness to such extent that, with a certain reduction of this sensitiveness, the usefulness of the arrangement, from a practical standpoint, is not diminished. By reason of a protective layer of this description the gradation 65 curve of the fluorescent layer is accordingly varied, so that the slow electrons of the space charge do not cause fluorescence, as they are unable to penetrate the protective coating. This protective coating may naturally also consist, for instance, of a conductive, for example extremely thin aluminium screen, which according to the invention then takes over at the same time the leak conductance of the disturbing charges.

A further arrangement of the invention re- 75

lates to a method for colour television. Where-
as in the case of the colour television methods
heretofore known the complete image for trans-
mission was transmitted successively in the dif-
ferent basic colours, the transmission of an image
point in the method according to the invention is
performed on each occasion in the three basic
colours within the completion period of one im-
age. A method of this kind is accompanied by
the appreciable advantage that the formation of
colour-seams, which are caused more particu-
larly by chronological parallax, is avoided. Ac-
cording to the invention, the fluorescent surface
is produced, preferably in the direction in which
line-scanning takes place, line by line from ad-
jacently disposed strips of different fluorescent
materials. As fluorescent materials there are
preferably employed three different substances
which, when met by electrons, each light up in
one of the three basic colours red, blue and green.
For example, potassium bichromate is suitable
for producing a red fluorescent colour, calcium
tungstate for producing a blue fluorescent colour,
and zinc silicate, cadmium tungstate or zinc sul-
phide for producing a green colour. In accord-
ance with the desired width of image point, each
image strip requires to be divided into three
coloured strips, which are scanned and trans-
mitted consecutively. These strips require to
possess various densities, or more or less dense
distribution of the crystals respectively, de-
pendent on the fluorescent-sensitive nature of
the fluorescent material employed, in order to
permit of an even width of line. The transmitter
and receiver tubes require to possess fluorescent
screens of a similar nature.

As it is done in the plain coloured transmission
the cathode ray of the transmitter tube is con-
ducted over the fluorescent area, and now scans
successively the strips composed of the different
fluorescent materials. If, for example, there is
taken the sequence: red, blue, green, the scan-
ning beam, the width of which accordingly
amounts to approximately $\frac{1}{3}$ of the desired im-
age-point width, will pass in strip-like fashion
in the same consecutive order: red, blue, green,
red, blue, green, etc. over the surface composed
of strips of the different materials. In order to
obtain in effect the same number of lines as in
the case of television without colours, the beam
accordingly requires to pass to three times the
extent over the surface. By sufficiently fine di-
visioning the surface of the transmission tube
will accordingly light up in white colour. This
surface is reproduced through the medium of an
optic on the image to be transmitted, and in ac-
cordance with the colour of this image a larger
or smaller proportion of the particular point of
light in the basic colour produced on the trans-
mission tube now passes for example through
the diapositive. At the same time the cathode
ray of the receiver tube is situated on the same
point, whereby naturally the cathode ray of the
receiver is required to pass over a fluorescent
surface strip of the same fluorescent colour.

In order upon the transmission of an image
point to afford the eye the appearance of a uni-
form colour, it is essential that the fluorescent
materials be so finely divided that their struc-
ture does not make itself noticeable. It is ac-
cordingly necessary that the receiving means be
so constructed that a very small angle of vis-
ibility is formed resulting in a subjective mixing
of the strip portions of the fluorescent surface

lighting in the three basic colours and belonging
to one element of the image.

Owing to the different fluorescent-sensitivities
of the various materials concerned as regards the
single basic colours, it is necessary for the pur-
pose of obtaining an image in natural colours
to so apportion the single fluorescent materials
that by reason of a cathode ray of constant dura-
tion and constant strength meeting against equal-
sized superimposed surface particles of an image 10
element the appearance of a certain image point
results.

According to the additional subject matter of
the invention, it is possible to also employ this
surface, composed of the different fluorescent ma- 15
terials, for the transmission of black-and-white
images or ordinary diapositives for obtaining a
white image.

If merely the problem is placed of producing
a white fluorescent surface it is obviously unnec-
essary to dispose the single fluorescent materials
in the form of strips. It is quite sufficient to
apply the same to the glass wall in any arrange-
ment as desired, attention being merely paid to
the fact that the distribution is sufficiently fine, 25
and that the apportioning of the different ma-
terials results in a white image upon constant ex-
citation, i. e., constant electric output—that is to
say, intensity and speed of the cathode ray.

To obtain a white image it is possible in ac-
cordance with the additional subject matter of
the invention to dispose the different fluorescent
materials in the form of superimposed layers,
whereby preferably the layer of greatest fluores- 35
cent sensitivity forms the surface directed away
from the cathode, whilst the surface with the
least fluorescent sensitivity is the one next to the
cathode. By suitable allotment and strength it is
also in this case readily possible to obtain an 40
admirable white luminous area.

The measures, as represented, may naturally
also be employed in conjunction with other tele-
vision methods, more particularly in the case of
those in which the image point scanning opera- 45
tion does not occur in time-linear fashion, but
in which the scanning speed is varied dependent
on the properties of the particular image point
to be transmitted.

The total arrangement is shown in Fig. 4. In
the latter 1 is the Braun tube, 2 the hot cathode 50
thereof, 3 the Wehnelt cylinder, 4 the anode, 5
and 6 the two pairs of deflecting plates, 7 the
fluorescent screen and 8 the lens system.

Additional to these, 15 is the photo-electric
cell amplifier, and 16 an apparatus for main sup-
ply furnishing the heating, anode and cylinder
potentials necessary for the operation of the
transmission tube. 17 is an image tilting means,
for example the frequency 25, and 18 a line tilting
means, for example the frequency 1500. These 60
two tilting devices are connected with both the
pairs of deflecting plates 5 and 6 of the trans-
mission tube 1 as well as the pairs of deflecting
plates 19 and 20 of the receiving tube 21.

As transmitter there was employed a cathode 65
ray tube having a new screen. The advantage of
allowing also the transmitter to operate with
Braun tubes resides not only in the elimination
of mechanically moved parts and in the slight
sluggishness of the transmitter, resulting only 70
from lighting and fading of the fluorescent
screen, but also in the fact that in the testing
apparatus, by parallel connection of the deflect-
ing plates, to which is connected line and image
potential, it is readily possible to produce the 75

requisite synchronism between the location of the point in transmitter and receiver. In the transmitter and the receiver the point scans synchronously an area, which, with correctly selected line and image potentials, appears in the form of an evenly luminous rectangle on the fluorescent screen. The luminous rectangle in the case of the transmitter tube illustrated in Fig. 1 is reproduced sharply on the diapositive or film 12 to be transmitted by means of a strong optic 8. Behind the diapositive there is arranged an opaque sheet 13 and the photo-cell 14. Each momentary position of the fluorescent point corresponds with a lighting current striking the photo-cell. The amount of light depends only on the transparency of the diapositive to be transmitted at the point where the fluorescent spot is reproduced at the particular moment through the medium of the optic. After sufficient, non-sluggish amplification of the photo currents there is a potential amounting to a few tens of volts available, which serves for the light control of the receiver tube. This arrangement permits good results, despite its great simplicity, by employing normal measuring tubes, main line apparatus and tilting apparatus, by the use of normal photo-cells, and by the use of good low-frequency amplifiers with a degree of amplification amounting between 10,000 and 100,000.

30 I claim:

1. In a Braun tube having means for generating and means for deflecting a cathode ray, a luminous screen applied to the end wall of said tube, the luminous material of said screen being 35 cadmium tungstate.

2. In a Braun tube having means for generating and means for deflecting a cathode ray, a luminous screen applied to the end wall of said tube, the luminous material of said screen having a fluorescent sensitiveness greater than the phosphorescence sensitiveness, said material being fixed on said end wall by a binding agent constituting at the same time a leak-conductance layer for leaking off charges from said screen.

45 3. In a Braun tube having means for generat-

ing and means for deflecting a cathode ray, a luminous screen applied to the end wall of said tube, the luminous material of said screen having a fluorescence sensitiveness greater than the phosphorescence sensitiveness, said material being applied to said end wall by a layer of potassium silicate.

4. In a Braun tube having means for generating and means for deflecting a cathode ray, a luminous screen applied to the end wall of said tube, the luminous material of said screen having a fluorescent sensitiveness greater than the phosphorescence sensitiveness, and a thin transparent protective layer applied onto said fluorescent screen material. 15

5. In a Braun tube having means for generating and means for deflecting a cathode ray, a luminous screen applied to the end wall of said tube, the luminous material of said screen having a fluorescent sensitiveness greater than the phosphorescence sensitiveness, and a layer of potassium waterglass applied onto said fluorescent screen material. 20

6. In a Braun tube having means for generating and means for deflecting a cathode ray, a luminous screen applied to the end wall of said tube, the luminous material of said screen having a fluorescence sensitiveness greater than the phosphorescence sensitiveness, and a layer in the form of an extremely thin aluminium screen applied onto said fluorescent screen material. 25

7. A fluorescent screen for Braun tubes for television reproduction consisting of materials generating light in the three basic colours upon being excited by the electrons of the cathode ray developed in said Braun tube, said materials being applied to the wall of said tube on a layer of a suitable binding agent such as potassium waterglass, said materials being arranged in the form of superimposed layers, the layer of greatest fluorescent intensity being situated on the side remote from the cathode, the layer of least fluorescent sensitivity being situated on the side directed towards the cathode. 35 40
